UNITED STATES PATENT OFFICE.

JOHN THOMAS BATTIS, OF GRAND RAPIDS, MICHIGAN.

EXTENSION-BRACKET.

No. 851,484.

Specification of Letters Patent.

Patented April 23, 1907.

Application filed March 16, 1906. Serial No. 306,466.

To all whom it may concern:

Be it known that I, JOHN THOMAS BATTIS, a citizen of the United States, residing at Grand Rapids, in the county of Kent and State of Michigan, have invented a certain new and useful Improvement in Extension-Brackets, of which the following is a full, clear, and exact description.

The primary object of this invention is to furnish to clothiers and others, a supporting device or bracket, on which a number of garments, such as coats, or pieces of fabric and other articles, may be suspended in a compact manner, and having the capacity of extension to spread apart the garments on the support to permit of their more complete inspection and display, and also to admit of their ready removal together with their hangers, the whole arranged in such way as to preserve the garments from careless and violent handling, to reduce their dust-exposed area, to keep them in shape, and to admit of their being readily enclosed within a cabinet, wardrobe or other projecting booth, or inclosure, from which they may be readily withdrawn as needed.

I have shown various embodiments of my invention herein, but without thereby intending to limit its variations within the principle of a telescopic arrangement of sections forming a garment-supporting member, and a run-rail from which it is suspended and upon which it is extensible or capable of being telescoped; the said sections arranged to receive and support the hangers and the garments hung thereon, all as I will proceed now more particularly to set forth and finally claim.

In the accompanying drawings illustrating my invention, in the several figures of which like parts are similarly designated, Figure 1 is a perspective view. Fig. 2 is a longitudinal section some parts broken away. Fig. 3 is a cross-section taken in front of the front supporting hanger. Fig. 4 is an elevation, on a smaller scale, showing the arrangement of the extension bracket within a cabinet or inclosure, with the parts enclosed in the inclosure. Fig. 5 is a similar view with the parts withdrawn. Fig. 6 is a side elevation with the outer end of the telescoping member fully extended. Fig. 7 is a bottom plan view of Fig. 6. Fig. 8 is a side elevation of a form of antifriction roller. Fig. 9 is a perspective view of a modification, including a swinging-run-rail. Fig. 10 is a longitudinal

section of the modification of Fig. 9. Fig. 11 is a sectional elevation of another modification. Fig. 12 is a perspective view of another form of outer hanger. Figs. 13 and 14 are cross-sections like Fig. 3, showing two other modifications. Fig. 15 is a perspective view of another modification.

Dealers in ready made garments are more and more discarding the old-fashioned tables on which the garments have been folded and piled in lots, and substituting for them various kinds of cases and racks or stands on which such garments as coats are hung by means of hangers, so that the garments may be better displayed, more easily handled and exhibited, preserved from wrinkling and crushing, and also more fully protected from dust. In the use of glazed cases or cabinets or wardrobes for this purpose, it is desirable to have some means by which the garments may be drawn out in lots for exhibition purposes, in contradistinction to being taken out one by one, and my invention furnishes such means, although its applicability and adaptability, of course, are not limited to this one use.

Referring now to Figs. 1, 2 and 3, 1 is a run-rail, preferably made of a rectangular bar of steel or other rigid material, and having at its ends lips 2 provided with means whereby it may be fastened in between the walls of a case, cabinet or wardrobe or other structure, in a substantially horizontal position. As shown, this run-rail has its opposite ends divided longitudinally and the adjacent parts turned to opposite sides of the run-rail, and at right angles thereto, so as to form, as it were, brackets, and these may have the screw-holes 3 through which screws may be passed into the woodwork of an inclosure to hold the run-rail in place. At or near the inner or rear end of the run-rail there is a notch 4 in its upper edge. Forward of the middle of this run-rail is a laterally projecting stop-pin 5. At the outer end of the run-rail is secured an open-sided hanger 6, here shown as a casting having one continuous side, the lower end of which terminates in a horizontally arranged pintle 7 upon which is mounted a roller 8, and the other side open and terminating a short distance below the run-rail, and forming a guard 9 to prevent the garment supporting member from jumping from the hanger. In order to effect, in an economical way, a rigid connection of the hanger with the run-rail,

the upper edge of the run-rail is notched and the inner portion of the hanger is recessed, so that these two parts may interlock somewhat after the manner of a mortise-joint, and then the parts may be further united by a screw or bolt 10. But any other method of connecting the run-rail and the hanger may be employed, and, as will presently appear, the hanger may be made adjustable on the run-rail.

The supporting member from which the garments are suspended is made up of a number of telescopic or extensible sections. Of these sections, that designated 11 may be a solid rod of metal, and solid because of the required rigidity and strength at this point. This rod 11 is provided with the hanger 12, projecting therefrom at right angles and slotted longitudinally so as to straddle the run-rail 1, and in this slotted portion are arranged below and above the run-rail the antifriction rollers 13 and 14. When the support is drawn back into its enclosed position, Figs. 2 and 4, the roller 14 drops into notch 4 and this displacement of what may be termed the center of gravity, in addition to the weight of the garments suspended from the supporting member, serve to lock the supporting member to the run-rail sufficiently firmly to prevent its displacement therefrom accidentally, and to admit of its displacement only by effort. The forward end of the rod 11 is grooved vertically and in this groove is arranged a roller 15. A second section of the supporting member is a tube 16, which is mounted to enclose and slide upon the rod 11, and is connected therewith by a coupling 17 having the flanged end 18 which hugs the rod sufficiently closely to serve as a stop against which the stop-collar 19 on the rod 11 abuts to limit the forward longitudinal movement of the tube 16 on the rod 11. The coupling 17 has the upwardly projecting ears 20 extending sufficiently far to embrace the sides of the run-rail 1, so as to prevent the said tube 16 from turning. Between the ears 20 is journaled an antifriction roller 21, which at times is in contact with the rod 11, as shown more particularly in Figs. 2 and 5. The roller 15 in the end of the rod 11 tracks upon the inside of this tube 16, and thus by means of these rollers 15 and 21 an antifriction bearing is provided, whereby the parts may be readily moved one with relation to the other. The tube 16 is supported also by the roller 8 in the hanger 6, and of course this roller will conform substantially in profile to the profile of the tube. A third section of the supporting member, 60 consists of the tube 22, fitted to slide inside of the tube 16 and having a length of sliding movement therein limited by a slot 23 in the bottom of the tube 16 which is engaged by a stop-pin 24 supported at the free end of the flat spring 25 fastened inside of the tube 22,

as by a screw 26. The engagement of the pin 24 in the slot 23 also serves to prevent the tube 22 from rotating within the tube 16. Also fastened inside of the tube 22 is a spring 27, having a bolt 28 adapted to engage a hole 29 inside of the tube 16 to lock the tube 22 within the said tube 16 so that these tubes will move together.

In order to unlock the tube 22 from the tube 16, a push-button 30 is mounted in the head 31 of the operating handle 32, and is connected with the free end of the spring 27 in such way that the spring may be pushed in to release the bolt 28 from the hole 29 so as to permit of the extension of the member 22. The push-button may be screwed into the spring 27 so as to be capable of being disengaged therefrom when the operating handle is to be removed, and at all other times this push-button prevents the operating handle from turning upon the tube 22.

The operating handle 32 may be screwed onto the end of the member 22.

As indicated in Fig. 3, this extension bracket is adapted for use with garment hangers having substantially hooked suspending mediums, here shown, in part, as a wire 33, having its suspending end provided with a roller 34, whose profile is substantially that of the supporting member of the bracket, so that these garment hangers may be readily applied to and removed from the supporting member through the open side of the hanger 6.

As shown in Fig. 4, when the run-rail 1 is mounted rigidly between two adjacent walls 35 and 36 of a cabinet or other inclosure or support, any number of garments may be suspended from the lower supporting member wholly within the inclosure. When it is desired to withdraw the garments for inspection, the operating handle 32 is grasped and pulled in the direction of the arrow, Fig. 4, and this pull results in sliding the tube 16 longitudinally outward upon the rod 11, and when the outward movement of the tube 16 has been arrested by contact of the flange 18 with the collar 19 on the rod 11, then by jerking the roller 14 out of the notch 4, both the rod 11 and tube 16 may be moved together outwardly until the outward movement is arrested by the hanger 12 coming into contact with the stop-pin 5, as indicated in Fig. 5. In this way the garment hangers will ride past the hanger 6, through its open side and outside of the inclosure, so as to be easily inspected. If it be desired to separate the garments on the supporting member for more complete inspection and without removing them from said member, then the push-button 30 is operated to release the bolt 28 from the tube 16 and the member 22 is drawn out as shown in Fig. 5, providing that much additional surface on which to separate the garments one from another.

The reverse operations serve to compact the garments again and shove them, together with the supporting member, back into the enclosure.

5 The antifriction rollers make the operation of the several parts of the bracket easy and practically noiseless. These rollers, as shown in Fig. 8, may consist of a roller-ring containing bearing-rollers between itself and the journal or pin.

The solid steel rod 11 gives strong and rigid leverage for the operation of the parts.

As already indicated, the invention is susceptible of various modifications, some of which I will now describe. Referring to Fig. 9, the run-rail here designated 37, is hinged to a bracket 38 fixed to a wall 39, and its outer end is supported by a stay-rod 40, fastened to the wall by an eye or other device 41, and the garment-supporting member is mounted upon this run-rail and the whole is capable of being swung back and forth relatively to the wall. In this instance also the open-sided hanger 42 has an eye 43 engaging the run-rail, and fixed or adjustable thereon, as may be required. The section 44 of the supporting member, has a roller-hanger 45 engaging the run-rail, and the member 46 has a pin 47 engaging a longitudinal slot 48 in the section 44, to limit its outward movement and also to prevent it from turning thereon. The section 44 has a roller 49 tracking in the section 46. The outer section 50 is arranged within the section 46, and has a roller 51 in its inner end. The section 50 has a catch 52 which engages a notch in the section 46 to limit the outward extension of the said section 50, and it also has a catch 53 adapted to engage a hole 54 in the section 46 to lock the two together in their closed position. The section 46 has at its forward end a roller 55 to support the section 50 in the extended position.

As shown in Fig. 11, wherein the parts are broken in order to bring the view within the drawing sight, the run-rail 56 is a tube mounted in brackets 57 fast to opposite walls, and in this case the depending open-sided hanger 58 is fast to the run-rail 56; the section 59 has the roller-hanger 60 suspending it from the said run-rail, and the telescoping sections 61 and 62 are connected with each other substantially as before, excepting that spring-bolts 63, 64 and 65 are used for stops.

All of these modifications contain the general principles first described, of an extension support running on a run-rail and in which there may be an initial partial extension, a secondary or other extension, and a final extension by means of which some of the garments supported may be brought to view, and then all of them brought to view and finally greater exhibition room afforded for the thus exposed complete contents of the

bracket, and all have antifriction rollers by which the movements of the parts may be rendered easy and noiseless.

The outer section may consist of the operating handle alone, and obviously any number of sections, two, three, or more may be employed, so that it is to be understood that the invention is not limited to the number of sections constituting the garment-supporting member, although the construction shown in Figs. 1 to 8 is preferred.

In the modifications shown in Figs. 9, 10, 11 and 12, various arrangements of antifriction rollers inside and outside are shown and require no further description. In Figs. 9, 80 11 and 12 the open-sided brackets are shown with concave rollers to support the garment-supporting member as before, and in Figs. 9 and 12 the bracket is shown with a guard-flap 85 at the left to reduce the liability of the garment-supporting member jumping from the roller.

As shown in Figs. 13 and 14 the front hanger may have the roller omitted, and in this case the part 66 may be broadened out 90 to serve as a slide-way for the extensible section. In Fig. 14 this front hanger is shown as having a foot 67 by which it and the front end of the run-rail may be secured overhead.

As shown in Fig. 14 the garment hanger 95 hook 68 may be used without a roller.

As shown in Fig. 15 the notch 4 may be omitted, or it may be replaced by some sort of catch or other device capable of holding the rear hanger in temporary engagement with the run-rail. Also in this view, is shown a rear hanger 69 without rollers and adapted to slide on the run-rail. Also in this view is shown a coupling 70 which omits the ears 20 and the roller bearing.

It is desirable to have such an engagement of the rear hanger with the run-rail as to prevent wobbling, and this construction is within my invention.

While I have designated the roller bearing in Fig. 8 as 21, it is to be understood that the construction illustrated is applicable to all of the roller bearings used throughout the structure, and it is also to be understood that I do not limit my invention to any particular kind of antifriction bearing.

In some cases the outermost section at the front may be omitted and the handle will then be attached, as by screwthreading, on the outer end of the second or extension section.

What I claim is:—

1. An extension bracket, comprising essentially a run-rail, a telescopic supporting member, a hanger rising from the supporting member into engagement with the run-rail at its rear end, and an open-sided hanger secured to and depending from the run-rail at the outer or front end and sustaining the supporting member at that end and permitting a

free movement of garments along the supporting member without obstruction from the open-sided hanger.

2. An extension bracket, having a run-rail notched at its inner or rear end, and an open-sided hanger at its outer or front end, and a garment-supporting member composed of a series of telescoping sections, the inner section having a roller-hanger fitted to the run-rail and normally held in the notched end of the run-rail, the second section having a stop-joint connection with the inner section and including a coupling engaging the run-rail so as to prevent rotation of said second section, and an outer section normally locked to the second section and provided with an operating handle whereby the second section may be extended with relation to the first section and these two sections moved along the run-rail by dislocating the first section from the notch of the run-rail.

3. An extension bracket, having a run-rail notched at its inner end, and an open-sided hanger at its front end, and a garment-supporting member composed of a series of telescoping sections, the inner section having a roller-hanger fitted to the run-rail and normally held in the notched end of the run-rail, the second section having a stop-joint connection with the inner section and including a coupling engaging the run-rail so as to prevent rotation of said second section, and an outer section normally locked to the second section and provided with an operating handle whereby the second section may be extended with relation to the first section and these two sections moved along the run-rail by dislocating the first section from the notch of the run-rail, and a stop on the run-rail for arresting the outward movement of the first section.

4. An extension bracket, having a run-rail notched at its inner end, and an open-sided hanger at its front end, and a garment-supporting member composed of a series of telescoping sections, the inner section having a roller-hanger fitted to the run-rail and normally held in the notched end of the run-rail, the second section having a stop-joint connection with the inner section and including a coupling engaging the run-rail so as to prevent rotation of said second section, and an outer section normally locked to the second section and provided with an operating handle whereby the second section may be extended with relation to the first section and these two sections moved along the run-rail by dislocating the first section from the notch of the run-rail, said outer section capable of being unlocked from the second section and extended therefrom a limited distance.

5. An extension bracket, comprising a run-rail having a notch at its inner end, a garment-supporting member having a solid inner section, a roller-hanger fixed to said

section and engaging the notch in the run-rail and adapted to run upon said run-rail, a second section, a coupling for slidably coupling it to the inner section, said coupling engaging the run-rail to hold said section upright 70 and having a roller bearing interposed between the run-rail and the inner section, an open-sided hanger on the outer end of the run-rail and in which hanger the garment-supporting member is arranged, and an operating handle applied to the second section.

6. In an extension bracket, a run-rail and a garment-supporting member suspended from said run-rail and capable of longitudinal movement thereon, said garment-supporting member having telescopic sections and a coupling having complementary members for connecting said sections and extending one of said members upwardly into sliding engagement with the run-rail so as to prevent 85 the turning of said supporting member.

7. In an extension bracket, a run-rail and a garment-supporting member suspended from said run-rail and capable of longitudinal movement thereon, said garment-supporting member having telescopic sections and a coupling connecting said sections and having a portion extending upwardly into sliding engagement with the run-rail so as to prevent the turning of said supporting member, and 95 an antifriction-roller borne by the coupling and interposed between the bottom of the run-rail and the top of the garment-supporting member.

8. In an extension bracket, a run-rail and a telescopic garment-supporting member suspended therefrom, one of the suspending devices comprising a hanger mounted upon the run-rail at its outer end and having a roller arranged beneath the garment-supporting 105 member and open at one side of the garment-supporting member.

9. An extension bracket for garments, comprising a run-rail, a support for said rail, telescoping sections, a movable hanger for suspending said sections from the run-rail at the inner end, and an open-sided hanger for suspending said sections from the run-rail at their outer end and permitting free movement of the garment hangers upon said telescoping sections past the open-sided hanger, and stops to limit the movement of said sections upon one another in extending the bracket.

10. In an extension bracket, the combination with suitable supports, of a run-rail, telescoping sections suspended from the run-rail at one end by a movable hanger, and at the other end by a hanger fixed to the run-rail above it and having a depending 125 open side which receives and supports the telescopic sections and permits their longitudinal movement thereon and also permits free movement of the garment hangers upon said sections past said open-sided hanger. 130

11. In an extension bracket, the combination with suitable supports, of a run-rail, telescopic sections suspended from said rail at one end by a movable hanger, a rigid open-sided roller-hanger for supporting said sections at the other end and permitting free movement of the garment hangers upon said sections past said roller-hanger, and stops to limit the movement of said sections relative to one another in extending the bracket. 30
12. In an extension bracket, a run-rail, a garment-supporting member suspended from said run-rail and extensible upon it, the suspension means including a hanger and a device for temporarily holding the hanger in a given position on the run-rail. 35
13. In an extension bracket, a run-rail, a garment-supporting member suspended from said run-rail, said suspension means including an open-sided front hanger having a guard at its open side to prevent the garment-supporting member from jumping off the hanger. 40
14. An extension bracket, comprising a run-rail, a garment-supporting member sus- 45

pended from said run-rail by means of a hanger at its inner end and an open-sided hanger at its front end, said garment-supporting member comprising a series of telescopic sections and the inner section having the inner hanger fixed to it and fitted to the run-rail and normally engaged therewith, said inner hanger engaging the run-rail so as to prevent wobbling of the garment-supporting member. 50

15. In an extension bracket, a run-rail, telescopic members suspended therefrom, and including an inner section provided with a handle and suitable catches whereby it may be extended and collapsed and the garments or fabrics arranged upon the support may be respectively separated and compacted. 55

In testimony whereof I have hereunto set my hand this 14th day of March A. D. 1906. 45

Corrections in Letters Patent No. 851,484.

It is hereby certified that in Letters Patent No. 851,484, granted April 23, 1907, upon the application of John Thomas Batts, of Grand Rapids, Michigan, for an improvement in "Extension-Brackets," errors occur in the printed specification requiring correction, as follows: In line 24, page 1, the word "projecting" should read *protecting*, and in lines 83-84, page 4, the words "one of said members" should be stricken out and inserted before the word "extending" in line 83, same page; and that the said Letters Patent should be read with these corrections therein that the same may conform to the record of the case in the Patent Office.

Signed and sealed this 7th day of May, A. D., 1907.

[SEAL.]

E. B. MOORE,
Acting Commissioner of Patents.

11. In an extension bracket, the combination with suitable supports, of a run-rail, telescopic sections suspended from said rail at one end by a movable hanger, a rigid open-sided roller-hanger for supporting said sections at the other end and permitting free movement of the garment hangers upon said sections past said roller-hanger, and stops to limit the movement of said sections relative to one another in extending the bracket. 30
12. In an extension bracket, a run-rail, a garment-supporting member suspended from said run-rail and extensible upon it, the suspension means including a hanger and a device for temporarily holding the hanger in a given position on the run-rail. 35
13. In an extension bracket, a run-rail, a garment-supporting member suspended from said run-rail, said suspension means including an open-sided front hanger having a guard at its open side to prevent the garment-supporting member from jumping off the hanger. 40
14. An extension bracket, comprising a run-rail, a garment-supporting member sus- 45

pended from said run-rail by means of a hanger at its inner end and an open-sided hanger at its front end, said garment-supporting member comprising a series of telescopic sections and the inner section having the inner hanger fixed to it and fitted to the run-rail and normally engaged therewith, said inner hanger engaging the run-rail so as to prevent wobbling of the garment-supporting member. 50

15. In an extension bracket, a run-rail, telescopic members suspended therefrom, and including an inner section provided with a handle and suitable catches whereby it may be extended and collapsed and the garments or fabrics arranged upon the support may be respectively separated and compacted. 55

In testimony whereof I have hereunto set my hand this 14th day of March A. D. 1906. 45
